ABSTRACT OF THE DISCLOSURE

A pedestal for supporting the rear end of a diving board above the ground including a deformable and resilient wall curving continuously about a substantially upright axis, with the wall carrying substantially the full vertical load transmitted between the diving board supported thereon and the ground, and deforming resiliently with flexing of the board.

This invention relates to a mounting for supporting the rear end of a diving board above the ground. More particularly, it relates to a pedestal-type mounting which is formed from a deformable and resilient material which functions, with flexing of a diving board, to impart a spring to the board which is in addition to that achieved internally in the board. The term "board" employed herein is intended to include materials other than wood.

Over the years, mountings have been proposed for diving boards which have been intended to provide maximum spring action at the forward end of a board. However, many of such mountings are unsatisfactory since they introduce a spring action at the forward end of a board which detracts from, rather than enhances, the natural spring characteristics of the board.

A general object of the present invention, therefore, is to provide a novel mounting for the rear end of a diving board which overcomes this deficiency, and which cooperates with a board to enhance the spring action available at the board's forward end.

More particularly, an object of the invention is to provide a novel pedestal mounting which includes a deformable and resilient wall which carries the full vertical load transmitted between the board and the ground, and which deforms resiliently with flexing of the board. According to a preferred embodiment of the invention the wall is formed from a resin-impregnated fiber glass mat which, through deformation as just mentioned, substantially enhances the spring action available at the forward end of the board.

Yet another object of the invention is to provide such a pedestal which is relatively simple to construct and install.

These and other objects and advantages attained by the invention will become more fully apparent as the description which follows is read in conjunction with the accompanying drawings, wherein:

FIG. 1 is a perspective view illustrating a pedestal constructed according to the present invention supporting a diving board above the ground adjacent the edge of a swimming pool;

FIG. 2 is an enlarged side elevation of the pedestal and diving board of FIG. 1, with portions of the pedestal broken away to illustrate details of the construction;

FIG. 3 is a cross-sectional view taken along the line 3—3 in FIG. 2; and

FIG. 4 is a cross-sectional view taken along the line 4—4 in FIG. 2.

Turning now to the drawings, and referring first to FIG. 1, at 10 is a conventional diving board having its rear end supported above the ground by means of a pedestal 12 which is constructed according to the present invention. The pedestal is secured in place by means of fasteners such as those shown at 14 which anchor its base to the ground. The rear end of the diving board is secured to the top of the pedestal by means of a plate 16, which overlies the top of the diving board, and bolts, or attaching means, 18. The forward end of board 10 extends outwardly over an edge of a swimming pool 20.

Considering the construction of pedestal 12, and referring to FIGS. 2—4, according to a preferred embodiment of the invention, the pedestal comprises upper and lower sections 22, 24, respectively. Upper section 22 is formed of a suitable deformable and resilient material such as a resin-impregnated fiber glass mat. It includes a central portion 22a which occupies a substantially horizontal plane with the pedestal mounted in place, and an upright, continuous curved wall portion 22b extending upwardly from the central portion. More specifically, and as can be seen in FIG. 4, wall portion 22b in horizontal cross section has an ovate configuration, with the major axis thereof extending from the front to the rear of the pedestal, and the minor axis extending at a right angle to the major axis. The upper part of wall portion 22b terminates in a portion 22c having a substantially rectangular outline when viewed in plan. Portion 22c directly underlies diving board 10.

Embedded in the mat which forms section 22, adjacent the forward and rear parts of portion 22c are elongated horizontal strengthening ribs 26, 28, respectively, which extend transversely of the pedestal. In the embodiment shown, such ribs are made of wood. Previously mentioned bolts 18 securing the rear of the diving board to the pedestal extend downwardly through suitable accommodating bores, or mounting means, provided in the mat and in rib 28, and are held in place by nuts, such as nut 29 (FIG. 2). Suitably secured above rib 26 is an elongated rubber mat, or rest, 30 which supports the under face of board 10 where it overlies rib 26.

Lower section 24 is formed from the same material as that used for section 22, and includes a central portion 24a which matches with section 22a, and a continuous curved wall portion 24b which extends downwardly, as shown, from the central portion. Sections 22, 24 are joined to perform as a unit by means of fasteners 32 securing together central portions 22a, 24a.

With the upper and lower sections of the pedestal joined together, wall portions 22b, 24b together form a wall in the pedestal wherein opposite sides, when viewed in vertical cross section (as, for example, in FIGS. 2 and 3), curve along opposed reversely bent courses. Further describing the wall, the same is symmetric relative to an upright plane 34 (FIGS. 3 and 4) which contains the longitudinal center line of the pedestal, but is nonsymmetric relative to an upright plane 36 (FIGS. 2 and 4) disposed as shown at a right angle to plane 34. Such nonsymmetry results from the fact, and considering now FIG. 2, that the part of wall portion 22b which is disposed forwardly of plane 36 extends further way from such plane as it curves toward the forward margin of portion 22c than does the part of the wall portion which is disposed rearwardly of plane 36. The wall herein curves about a upright axis coinciding with the line of intersection of planes 34, 36.

Considering now how pedestal 12 performs, with diving board 10 in a nonflexed state, which is the condition for the board illustrated in solid outline in FIG. 2, the upper and lower sections of the pedestal occupy the positions where they are shown in solid outline. When the diving board is flexed to its dash-dot outline position, for example due to a person jumping on the forward end of the board, the pedestal deforms to have the con-

figuration shown in dash-dot outline in FIG. 2. More specifically, the forward parts of wall portions 22b, 24b are compressed and shifted rearwardly somewhat from their solid outline positions, and the rear parts of the wall portions are tensed and also urged rearwardly of their solid outline positions. Because of the stressed conditions which result in the pedestal due to such deformation, and because of the resilience present in the fiber glass mat making up the pedestal, the same imparts a spring to board 10 which enhances the spring action produced at the forward end of the board. More specifically, the pedestal imparts a spring which contributes to, but does not override, the natural spring present in the board.

Thus, the invention provides a novel pedestal for supporting the rear of a diving board, which pedestal deforms resiliently with flexing of the board in a manner enhancing the spring action produced at the forward end of the board. An important feature of the invention is that the enhanced spring action results from the resilience present in the wall of the pedestal through which substantially the full vertical load from the board is transmitted to the ground. Also contributing is the fact that the wall has a configuration readily permitting stressing and deforming to positions such as those shown in dash-dot outline in FIG. 2. Accordingly, no springs are required to be attached to the board.

Because of the ovate cross-sectional outline which the wall has, when viewed as in FIG. 4, maximum strength is obtained in the construction, with the wall permitted to deform, but not to deform so much as to fatigue.

Further, it will be noted that the pedestal proposed is relatively simple in construction, and can readily be mounted in place. While the pedestal shown comprises upper and lower sections, which are preferred since they can be formed through relatively simple molding techniques, it should be appreciated that the pedestal may be formed as all one piece.

While an embodiment of the invention has been described herein, it is appreciated that variations and modifications may be made without departing from the spirit of the invention. Accordingly, it is desired to cover all such variations and modifications which become apparent to those skilled in the art and which come within the scope of the appended claims.

It is claimed and desired to secure by Letters Patent:

1. A spring-imparting pedestal for supporting the rear end of a diving board above the ground comprising, a deformable and resilient wall curving continuously about a substantially upright axis, said wall having front and rear sides, and being constructed to carry substantially the full vertical load transmitted between such a board supported on the pedestal and the ground, and to deform resiliently with flexing of the board, and mounting means located adjacent the rear side and near the top of said wall accommodating attachment of a diving board with the board extending

from said mounting means toward and laterally beyond said front side of said wall.

2. The pedestal of claim 1, wherein opposite sides of said wall, with the wall viewed in cross section in all planes containing said axis, curve along opposed reversely bent courses.

3. The pedestal of claim 2, wherein said wall, when viewed in cross section in a plane normal to said axis, has a substantially ovate configuration, with the major axis of such configuration extending between the front and rear of the pedestal, and the minor axis thereof extending at a right angle to said major axis.

4. The pedestal of claim 3, wherein said wall is symmetric relative to an upright plane containing said major axis, and nonsymmetric relative to an upright plane containing said minor axis.

5. The pedestal of claim 4, wherein, considering the upper portion of said wall, the part thereof disposed forwardly of the upright plane containing said minor axis extends further away from said plane than does the part which is disposed rearwardly of such plane.

6. The pedestal of claim 5, wherein said wall is formed from a resin-impregnated fiber glass mat.

7. The pedestal of claim 6 which includes upper and lower sections that are joined together to perform as a unit.

8. The pedestal of claim 1 which further comprises a rest located adjacent the top and near the front side of said wall for engaging the bottom side of a diving board supported on the pedestal.

9. The pedestal of claim 1 which further comprises a strengthening rib positioned adjacent said mounting means.

10. The pedestal of claim 8 which further comprises a strengthening rib positioned adjacent said rest.

11. The combination of an elongated diving board having front and rear ends, a pedestal beneath the rear end of said board supporting the board above the ground, said pedestal comprising a deformable and resilient wall curving continuously about a substantially upright axis, and attaching means securing said rear end of said board adjacent the rear side of said pedestal whereby said wall carries substantially the full vertical load transmitted between said board and the ground.
